UNITED STATES PATENT OFFICE.

RAYMOND M. ANDERSON, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,063,148.

Specification of Letters Patent.

Patented May 27, 1913.

Application filed July 26, 1912. Serial No. 711,619.

To all whom it may concern:

Be it known that I, RAYMOND M. ANDERSON, a citizen of the United States, and resident of Chicago, in the county of Cook and State of Illinois, have invented a certain new and useful Improvement in Carbureters, of which the following is a full, clear, concise, and exact description, reference being had to the accompanying drawings, forming a part of this specification.

My invention relates to the art of carburetation and contemplates an improved carbureter for association with internal combustion engines.

It is the primary object of my invention to provide a carbureter in which the most efficient mixtures are produced for the various speeds; that is, it is my primary object to provide a device whereby the constituent proportions of the mixture may be determined, maintained, and graded, for the different engine speeds, automatically and without adjustments other than those necessary preliminarily.

So far as the specific device which I shall describe herein is concerned, it is an important feature that I obtain the desirable mixture regulation without employing any moving parts other than the manually operated throttle.

I secure the advantages of my invention by the employment of two fuel nozzles, connected with a common supply, to which nozzles fuel is fed through gaged passageways, under the influence of varying pressures and varying aspirating effects, so that the flows to and from both the nozzles may vary according to the engine demand, to secure the proper quantity of mixture and, as well, the proper quality.

My invention is illustrated in the accompanying drawing, in which—

Figure 1 is a view, partly in side elevation and partly in axial section, of my improved carbureter; and Figs. 2 and 3 are sectional views of different forms of nozzles which will be referred to.

The carbureter casing is illustrated at 4 and it will be seen that it provides a carbureting chamber 5, surrounded by a water jacket 6, an air inlet at 7, and a mixture outlet at 8. A flange 9 surrounds the mixture outlet so that the device may be attached to the manifold of an engine, and a throttle 10, manually operative, is mounted upon a

transverse shaft 11, in the passageway 8, so as to control the connection between the carbureter and the engine.

The casing provides the carbureting chamber 5 and the passageway 8 by means of its central bore, and an auxiliary member 12, which forms a Venturi tube, is disposed at the lower end of this bore so as to form an entrance to the carbureting chamber. This Venturi tube member 12 is held in place by means of a set screw 13 engaging in the casing 4. The casing 4 is provided with a laterally extending shelf 14 and the float chamber 15 is supported upon this shelf. The float chamber is connected with a main supply by means of a valve controlled passageway, the valve being operated by any of the float chamber mechanisms well known to those skilled in the art. These particular details are of no moment here and I shall therefore not refer to them. It is sufficient to point out that the dot-and-dash line *a* represents the fuel level maintained in the float chamber. The float chamber is provided with the atmosphere inlet 16.

The float chamber is connected by means of a passageway 17 with a part 18 of the casing axially below the Venturi tube. A nozzle 19 is mounted in this part of the casing, so as to extend axially up into the Venturi tube, terminating near the restricted portion thereof, and is held in place by means of a screw plug 20 having the restricted passageway 21 therethrough. The casing, at this point, is formed into a well 22 which communicates with the interior of the nozzle 19 by means of openings 23, 23 leading radially into the nozzle bore at the restricted end of the plug 20. At its upper end, this well is connected with the atmosphere through an opening 23 in a plug 24, the plug being provided so that the size of the opening may be initially adjusted.

An auxiliary reservoir in the form of a tube 25 is provided. This reservoir passes up through the well 22, but does not communicate therewith, screwing into the part 26 at its top. The tube 25 at its lower end is provided with the restricted inlet 27 which communicates with the passageway 17 leading from the float chamber, and the interior of the reservoir 25 is exposed at its top to the pressure in a chamber 28 surrounding the Venturi tube and exposed to the pressure therein through the passage-

110

ways 29 and 30. The chamber 28 is also connected with the atmosphere by means of a restricted passageway 31 which is in a plug 32 screwing in the casing. In this way, the plugs may be interchanged for initial adjustment, since the relative sizes of the openings to the atmosphere and to the pressure in the Venturi tube or carbureting chamber is very important. A fuel tube 33

10 extends down into the reservoir 25, to a point near the bottom thereof, and extends upwardly so that its end may open into the passage above the throttle, as illustrated. The throttle is shown in its closed position

15 and it is illustrated as being cut out to accommodate the end of the tube 33.

The operation of my improved device is as follows: When the motor is at rest, the liquid fuel, such as gasolene, may be assumed to be standing at the level indicated by the dot-and-dash line *a*. It will be seen that in this condition the fuel has passed through the restricted passageway 27 into the reservoir 25 and has also passed through

25 the restricted opening 21 into the nozzle 19 and the well 22. When the throttle is slightly open and the engine is turned over, air will be drawn past the outlet of the tube 33 at a comparatively high rate of speed and

30 the gasolene will be drawn up through the tube 33 out of the reservoir 25 into the manifold of the engine in practically its raw state. This results in a very rich mixture, desirable for starting purposes, and it is

35 clear that the level of the fuel in the reservoir 25 will drop down to the bottom of the tube 33. It is to be noted that the surface of the fuel in the reservoir 25 is exposed to the pressure in the chamber 28 which, in

40 turn, is subject to the pressure and the variations in pressure in the Venturi tube or carbureting chamber. It is thus clear that as the suction in the Venturi tube increases, the pressure in the chamber 28 will be lowered, and the rate at which the fuel passes through the restricted opening 27 into the reservoir 25 will vary accordingly. It has been found by experiment, however, that this variation, while highly desirable and

45 productive of the best sort of a mixture, is too marked for practical purposes, unless properly moderated and I have secured this moderation by means of the restricted passageway 31 to the atmosphere. The passageway is restricted to such an extent that it cannot satisfy the suction created in the chamber 28 and it therefore follows that the pressure on the surface of the fuel in the reservoir 25 is lessened, as the engine speed increases, so that, as before pointed out, the flow through the passageway 27 is varied accordingly. As the throttle is opened wider, the flow through the restricted passageway 27 is gradually increased and the

55 flow from the end of the tube 33 is also in-

creased, but after the throttle has been opened wide to a certain extent, the flow from the tube 33 is insufficient to maintain the proper quality for the quantity of air now being admitted into the engine. At this point, however, the suction around the nozzle 19 in the Venturi tube has become great enough to lift the fuel out of the nozzle and in this way the amount of fuel necessary to complete the proper proportion is secured. When the proper amount of suction is initiated around the nozzle 19, the nozzle and the well are affected and they are gradually emptied. During all this time, however, the fuel is flowing through the restricted passageway 21 at a rate depending upon the variable head over the nozzle and also upon the variable suction effect of the Venturi tube. If the suction is increased sufficiently, the well and the nozzle 19 are entirely emptied and fuel is drawn through the restricted passageway 21 by means of the suction on the nozzle 19 and also by means of the aspiration produced by the rush of air coming in by way of the passageway 23, through the well and up through the nozzle carrying the fuel with it. As the higher engine speeds are still further increased, the aspiration effect upon the nozzle 19 is correspondingly increased and the flow through the passageway 21 varies accordingly. It will be seen that the flow through the passageway 21 is accentuated by reason of the fact that it is below the fuel level maintained in the float chamber. The accentuation of the natural flow through the passageway 21 is, of course, more in proportion to the entire flow at the lower speeds than at the higher speeds since, at the higher speeds, the flow as determined by the varying suction effects on the nozzle is so much greater. In this way, although the quantity of the fuel and air is increased sufficiently on high speeds, the proportion may be changed slightly so that the desirable leaner mixture may be had on the higher speeds.

It will be clear that the opening 16 at the top of the float chamber provides for the constant atmospheric pressure on the top of the valve in the float chamber. Initial adjustments, for different engines, and under different conditions, are necessarily made in the sizes of the various passageways for air and fuel, the proper relation of areas being always maintained. The tube 27 is removable, upon the removal of the plug 27', and another tube, having a different size opening 27 may be readily substituted therefor. The plugs 20 may be removed upon the removal of the plug 20' and a different plug having a different size opening 21 may be substituted therefor so as to get the mixture proportions proper for maximum speed. The plugs may also vary in length, as illus-

trated in Figs. 2 and 3, and plugs of different length may be inserted to secure various adjustments. It is obvious that the higher the plug extends the less will be the accentuation due to the natural passage of the flow through the passageway 21.

I claim as new and desire to secure by Letters Patent:

1. In a carbureter, a carbureting chamber, 10 a fuel jet therein, a constant level supply chamber feeding said fuel jet and exposed to atmospheric pressure, an auxiliary reservoir fed from said constant level supply chamber, an auxiliary fuel jet discharging 15 into said carbureting chamber and fed from said auxiliary reservoir, an atmosphere inlet for said auxiliary reservoir, and means for maintaining a sub-atmospheric pressure in said auxiliary reservoir during operation of 20 said carbureter.

2. In a carbureter, a carbureting chamber, a fuel jet therein, a constant level supply chamber feeding said fuel jet and exposed to atmospheric pressure, an auxiliary reservoir 25 fed from said constant level supply chamber, an auxiliary fuel jet discharging into said carbureting chamber and fed from said auxiliary reservoir, an atmosphere inlet for said auxiliary reservoir, and means for 30 maintaining a sub-atmospheric pressure in said auxiliary reservoir during operation of the carbureter comprising a duct for the passage of air only, communicating with said carbureting chamber and with the auxiliary reservoir above the level of the liquid 35 therein.

3. In a carbureter, a carbureting chamber, a fuel jet therein, a constant level supply chamber feeding said fuel jet and exposed 40 to atmospheric pressure, an auxiliary reservoir fed from said constant level supply chamber, an auxiliary fuel jet discharging into said carbureting chamber and fed from 45 said auxiliary reservoir, an atmosphere inlet for said auxiliary reservoir, and means for maintaining a variable sub-atmospheric pressure in said auxiliary reservoir depending upon the suction of the engine to give a 50 variable supply per unit of time to said auxiliary fuel jet according to the suction of the engine.

4. In a carbureter, a carbureting chamber, a fuel jet therein, a constant level supply chamber feeding said fuel jet and exposed 55 to atmospheric pressure, an auxiliary reservoir fed from said constant level supply chamber, an auxiliary fuel jet discharging into said carbureting chamber and fed from 60 said auxiliary reservoir, a restricted atmosphere inlet for said auxiliary reservoir, and means for maintaining a sub-atmospheric pressure in said auxiliary reservoir during 65 operation of the carbureter.

5. In a carbureter, a carbureting chamber, 65 a fuel jet therein, a constant level supply

chamber feeding said fuel jet and exposed to atmospheric pressure, an auxiliary reservoir fed from said constant level supply chamber by way of a restricted passageway, an auxiliary fuel jet discharging into said carbureting chamber and fed from said auxiliary reservoir, a restricted atmosphere inlet for said auxiliary reservoir, and means for maintaining a variable sub-atmospheric pressure in said auxiliary reservoir upon the 70 liquid therein, depending upon the suction of the engine, to give a variable feed to said auxiliary reservoir through the restricted passageway leading from said constant level supply chamber according to the suction of 75 the engine.

6. In a carbureter, a carbureting chamber, a Venturi tube leading thereto, a fuel nozzle extending into said Venturi tube, an air inlet for said Venturi tube, a constant 80 level supply chamber for liquid fuel, a well at the bottom of said nozzle, a restricted jet connecting said supply chamber and said well, an air inlet for said well, the air entering by said last-named inlet being adapted to draw fuel from said jet by suction and to pass with said fuel out of said nozzle, a reservoir, restricted means connecting said supply chamber and said reservoir, means for connecting the chamber over the normal 85 level of the liquid in said reservoir with the interior of the Venturi tube, and a nozzle leading from said reservoir to the carbureting chamber.

7. In a carbureter, a carbureting chamber, a Venturi tube leading thereto, a fuel nozzle extending into said Venturi tube, an air inlet for said Venturi tube, a constant level supply chamber for liquid fuel, a well at the bottom of said nozzle, a removable 100 restricted jet connecting said supply chamber and said well, an air inlet for said well, the air entering by said last-named inlet being adapted to draw fuel from said jet by suction and to pass with said fuel out of 105 said nozzle, and the height of the jet outlet taking part in determining the flow therefrom, a reservoir, restricted means connecting said supply chamber and said reservoir, means for connecting the chamber over the liquid in said reservoir with the interior of the Venturi tube, and a nozzle 110 leading from said reservoir to the carbureting chamber.

8. In a carbureter, a carbureting chamber, a Venturi tube leading thereto, a fuel nozzle extending into said Venturi tube, an air inlet for said Venturi tube, a constant level supply chamber for liquid fuel, a well at the bottom of said nozzle, a removable 115 restricted jet connecting said supply chamber and said well, an air inlet being adapted to draw fuel from said jet by suction and to pass with said fuel out of said nozzle, and the height of the jet outlet taking part in 120

125

determining the flow therefrom, a reservoir, restricted means connecting said supply chamber and said reservoir, means for connecting the chamber over the liquid in said 5 reservoir with the interior of the Venturi tube, a throttle, and a nozzle leading from said reservoir to a point on the engine side of the throttle.

9. In a carbureter, a carbureting chamber, a Venturi tube leading thereto, a fuel nozzle extending into said Venturi tube, an air inlet for said Venturi tube, a constant level supply chamber for liquid fuel, restricted means for connecting said supply 15 chamber with said nozzle, a reservoir in the

form of a removable tube, said reservoir having an atmosphere inlet, restricted means connecting said supply chamber and said reservoir, means for connecting the chamber over the liquid in said reservoir 20 with the interior of the Venturi tube to maintain sub-atmospheric pressure in said reservoir, and a nozzle leading from said reservoir to the carbureting chamber.

In witness whereof, I hereunto subscribe 25 my name this 24th day of July, A. D., 1912.

RAYMOND M. ANDERSON.
